DESIGN FOR A BOTTLE

George Smith, Jr., Olean, N. Y., assignor to Olean
Glass Company, Olean, N. Y., a corporation
of New York

Application August 4, 1936, Serial No. 64,242

Term of patent 7 years

To all whom it may concern:

Be it known that I, George Smith, Jr., a citizen of the United States and residing at Olean, in the county of Cattaraugus and State of New York, U. S. A., have invented a new, original, and ornamental Design for a Bottle, of which the following is a specification, reference being had to the accompanying drawing, forming a part thereof, wherein:

Figure 1 is a view in elevation of a bottle ornamented with my design and showing the ornamentation in the arch-like section at the bottom of each vertical panel; Figure 2 is a view in

elevation of the bottle showing the ornamentation and the arch-like sections of the remaining panels of the bottle; and Figure 3 is a top plan view of the bottle shown in Figures 1 and 2. As shown in Figure 3, the rear face of the bottle is plain and unornamented and is substantially twice the width of the ornamented panels of the bottle.

I claim:

The ornamental design for a bottle as shown and described.

GEORGE SMITH, JR.
